(57) CLAIM

The ornamental design for a golf iron head, as shown and described.

DESCRIPTION

FIG. 1 is a perspective view of a golf iron head showing our new design;

FIG. 2 is a front elevational view of the golf iron head of FIG. 1;

FIG. 3 is a rear elevational view of the golf iron head of FIG. 1;

FIG. 4 is a top view of the golf iron head of FIG. 1;

FIG. 5 is a bottom view of the golf iron head of FIG. 1;

FIG. 6 is a heel end view of the golf iron head of FIG. 1; and,

FIG. 7 is a toe end view of the golf iron head of FIG. 1. The broken lines shown in FIGS. 1, 2 and 4 are for illustrative purposes only and form no part of the claimed design.
